UNITED STATES PATENT OFFICE.

REGINALD REYNOLDS, OF RIVERSIDE, CONNECTICUT.

THREAD PACKAGE OR HOLDER.

1,343,934.

Specification of Letters Patent. Patented June 22, 1920.

Application filed March 1, 1920. Serial No. 362,237.

To all whom it may concern:

Be it known that I, REGINALD REYNOLDS, a citizen of the United States of America, residing at Riverside, Connecticut, have invented a new and useful Thread Package or Holder, of which the following is a specification.

My invention relates particularly to an improved means for packaging thread, yarn, silk, floss or the like in short lengths. The term thread will be used herein for convenience as applying to either yarn, silk, cotton, linen, leather or other similar strands for various purposes.

15 The main object is to provide a simple and inexpensive form of package in which threads in short lengths may be packed and sold, and from which package individual lengths of thread may be readily withdrawn 20 one at a time without tangling or knotting the remaining strands.

In its preferred form the bunch or bundle 25 or group of threads is folded or doubled near its central portion and wrapped with a special wrapper of paper or other suitable material. The wrapper has a body portion and a locking portion preferably formed by notching or otherwise cutting one edge of a blank. The remainder of the blank is so 30 designed as to facilitate wrapping the thread and sealing the package without danger of misplacing the thread or getting glue or paste on the thread and at a minimum expense.

35 Figure 1 shows the preferred form of blank for making my improved package.

Fig. 2 shows the first step in wrapping the thread in the blank.

Fig. 3 shows the second step in wrapping 40 the thread in the blank.

Fig. 4 is a sectional view of the plane of the line 4-4 of Fig. 3.

Fig. 5 is a sectional view of the finished 45 package.

Fig. 6 shows a slightly different form of blank with the thread in place ready to be wrapped.

Fig. 7 is a side view of a finished package 50 formed from the blank of Fig. 6.

Fig. 8 is a sectional view on the plane of the line 8-8 of Fig. 7.

Fig. 9 is a sectional view on the plane of the line 9-9 of Fig. 7.

The main body of the blank 10 has an extension 11 forming a neck connected to the body of the blank along the line 12 where it

is adapted to be folded. The threads 13 are looped about the end of the extension 11, as shown in Fig. 2. The portion 14 of the blank serves to hold the ends of the thread 60 in place when folded as shown on the dotted lines of Fig. 2. These portions 11 and 14 are separated preferably by a slot, notch or thread passage 15 in the edge of the blank which for convenience in operation is made 65 inclined, as shown.

The main body of the blank is preferably made up of three longitudinal strips 16, 17 and 18, which are adapted to be folded relative to each other along the lines 19 and 20. 70 To facilitate this folding the blank may be creased or indented. Preferably, the body of the blank is made long enough so that the end 21 will cover the loop of the thread when the package is finished. The 75 edge of the blank is preferably gummed along the edge 22 or provided with paste or other suitable adhesive.

In making up a package, the thread is first looped about the extension 11 which 80 is folded over as shown in Fig. 2. The covering flap 14 is then folded over as indicated by the dotted lines in Fig. 2 so as to loosely hold the ends of the thread in position. The blank is then folded along 85 the line 19 so that the portion 17 will gather up any stray threads and bunch them together neatly. The blank is then folded on the line 20 so that the portion 18 with the adhesive strip 22 will be brought over on 90 to the opposite side of the package where there is no possibility of the glue coming in contact with any stray thread.

The form of invention shown in Figs. 6 to 9 inclusive has been divided out of my 95 application #330,253, filed Oct. 13th, 1919, and the present application is therefore a continuation of the former as to this form. In this case the blank 10' has a neck or extension 11' about which the threads are 100 looped and a cover flap 14' separated from the portion 11' by the notch or slit 15'. When this package is completed, a portion 13' of the thread is left displayed at one end. In this form, individual threads may 105 be withdrawn from either end of the package, whereas in the form shown in Figs. 1 to 5 inclusive, the threads can be withdrawn only from the cut end of the thread.

The material from which the wrapper is 110 made is preferably paper which is more or less stiff so as to offer the necessary resist-

ance to the pulling of the threads from the package. The form of package shown in Figs. 1 to 5, is particularly adapted to be put up either by hand with unskilled labor, 5 or by machine, and the resulting package is not only neat in appearance, but adequately protects the thread and provides a convenient means for shipping, display, and sale, as well as for convenient use.

10 I claim:

1. A thread package comprising a wrapper having a transverse slot in one longitudinal edge intermediate its ends for dividing said edge into an extension member 15 and a cover flap, a bundle of threads looped over said extension member at one end and extending to the other end past the cover flap, said extension member when folded once upon said wrapper inclosing half of the threads which are in engagement with the extension member, said cover flap when folded once upon said wrapper inclosing all the threads which are in engagement with the flap, said extension member and cover flap 25 being folded a second time onto said wrapper for inclosing the threads not covered

by the extension member, said folded parts being folded again on said wrapper and secured thereto.

2. In the combination set forth in claim 30 1, said extension member being spaced from one end of the wrapper so that the looped over threads in engagement with the extension member will not project beyond the end of the package. 35

3. A thread package comprising a wrapper, an extension member extending from one longitudinal side thereof, a cover flap extending from the same side of said wrapper and located adjacent said extension member, a bundle of threads looped over said extension member at one end and extending past said cover flap, said extension member when folded once on said wrapper inclosing half of the threads which are in 40 engagement with the extension member, said cover flap when folded once on said wrapper inclosing all the threads which are in contact with the flap, said folded parts being secured together to form a package. 50

REGINALD REYNOLDS.
